RAIL JOINT

Charles D. Young, Haverford, Pa.

Application February 2, 1931, Serial No. 512,868

6 Claims. (Cl. 238—244)

This invention relates to rail joints, and more particularly to a rail joint construction in which there are combined with one or more joint bars shims or liners disposed in such manner above the head and below the foot portion of the joint bar or bars as to provide freedom for the rail at certain regions when the rail is subjected to a moving load and intimate bearing contact with the rail at other regions of the joint. More specifically, the joint construction of this invention compensates for the tendency of rail ends to dip or bend downward at the joints forming what is commonly called "low joints." Such deflection of rail ends at the joints produces depressions below the normal plane of the running surfaces of the rails and causes pounding of the moving loads at the depressed areas. As the result of excessive pounding, a rail joint construction will wear rapidly and will cease to operate efficiently.

Heretofore numerous attempts have been made to compensate for wear at rail joints, and I am fully aware that it has been proposed to provide various forms of shims between joint bars and rails and to provide special forms of joint bars with bearing surfaces deflected from true parallelism with the longitudinal axes of the rails. My invention, however, is adapted to be applied to standard forms of joint bars in which there is no deflection in the head, web or foot portions; and the invention is particularly characterized by an arrangement of shims at a rail joint which in effect produces an arched joint bar trussing the rail ends up at the joint by providing head contact at the rail ends and base contact at the bar ends.

Other objects and advantages characterizing this invention will become more fully apparent from the detailed description of an embodiment or example thereof which follows hereinafter, having reference to the accompanying drawing, wherein:

Fig. I is a side elevation of a rail joint embodying a continuous joint bar.

Fig. II is a cross section of the same, taken as indicated by the lines II—II of Fig. I.

Fig. III is a cross section of the same, taken as indicated by the lines III—III of Fig. I.

Fig. IV is a perspective view of the head shim shown in Figs. I and II.

Fig. V is a perspective view of the base shims shown in Figs. I and III.

Fig. VI is a view similar to Fig. II, but showing the application of the head shim to a different joint bar of the angle type; and,

Fig. VII is a view similar to Fig. III, showing

the application of base shims to a joint bar of the angle type.

In the drawing, adjoining rails are designated at 1, the rails being of standard form and comprising head portions 2, web portions 3 and flanged bases 4. The joint bars 5 selected for illustration in Figs. I, II and III are of uniform height and section throughout, and of less fishing height than the fishing height of the rails, and are of the continuous type, each having a head portion 6, a web portion 7, and a base portion 8 which extends around the flanges 4 of adjoining rails enveloping their top slopes 9 and bottom surfaces 10. There are no deflections in the joint bar 5, the inner surfaces of which are parallel to the corresponding rail surfaces. Spaced longitudinally throughout each joint bar 5, there are holes 11 aligned with corresponding holes 12 in the webs 3 of the rails 1, these holes being adapted to accommodate bolts 13 for flexibly securing the bars 5 to the rails 1. Between the joint bar and the bolt heads 13, or nuts 14 where the bolts are alternately reversed, plates 15 are preferably interposed, there being one such plate on each side of the joint. As thus far described, the rail joint construction involves a common form of rolled bar. It is to be understood, however, that the general form of joint bars to which my invention may be applied admits of considerable variation, for example, with respect to the cross-sectional shape of head and foot portions, the contour of the bearing surfaces and the distance at which the web of the joint bar is spaced from the rail.

Above the medial portions of the joint bars 5, there are shown metal head shims or liners 16, of less length than the joint bar 5 whereof one is illustrated in perspective in Fig. IV. Each such shim is of angular section and is adapted to fit snugly beneath the head portions 2 of the rails 1, one leg 17 contacting with the undersides of the head portions, and the other leg 18 contacting with the surfaces of the web portions 3 of the rails 1. The leg 18 of each head shim 16 is provided with a depending projection 19 which is accommodated between two bolts 13 at the center of the rail joint. This depending projection 19 serves to maintain the shim 16 in a predetermined longitudinal position.

At the ends of the joint bars, additional metal shims 20 and 21 of the form illustrated in perspective in Fig. V are interposed between the base flanges of the adjoining rails and the joint bars 5. These shims are also of angular cross section, each comprising a vertical leg 22 adapted to

bear against the rail web 3, a leg 23 adapted to bear against the top slope 9 of the flanged base 4, and a horizontal leg 24 adapted to bear against the bottom 10 of the flanged base 4 of a rail 1. 5 The vertical leg 22 is in each instance provided with an upstanding projection 25 which is accommodated between a pair of bolts 13 at the end of the rail joint. The upstanding projections 22 serve to maintain the shims 20, 21 in their 10 proper longitudinal positions.

It will be noted that each head shim 16 provides a bearing surface intimately engaging the rail ends beneath their heads and at the medial portion of each joint bar, and affords head clearance 15 between the corresponding bar and those regions of the rails which are opposite the bar ends. On the other hand the base shims 20, 21 provide bearing surfaces intimately engaging the rail bases at the bar ends with clearance between 20 the bar and the rail bases at the region beneath the head shim 16. Accordingly, the shims 16, 20 and 21 provide in effect a three-point contact 25 between bar and rails, one point or area of contact being between the heads of adjoining rail ends and the middle of the bar, and the other points or areas of contact being between the bar ends and the rail bases.

When the nuts 14 are tightened with the shims in place, the rail ends are trussed up to better resist downward depression incident to the passage 30 of heavy loads, there being, however, clearance between the rail bases at the rail ends and the joint bar to provide freedom for the rail at this region without restraining action between the rail ends and the joint bar. The shims are preferably 35 so disposed that the ends of the base shims 20, 21 are in vertical line with the ends of the head shim 16.

In Figs. VI and VII, joint bars 5a of the angle 40 bar type are shown, each such bar comprising a head portion 6a, a web portion 7a, and a base portion 8a, the inner bearing surface of which does not extend around the flanged base 4 of the rails 1 but conforms to their top slopes. Shims 45 16a, 20a and 21a are disposed in each instance between the bar 5a and the rails 1 in the same manner as described above, except that the base shims 20a and 21a engage only the top slopes of the flanged bases 4 of the rails 1. Accordingly, 50 the head shims 16a are of the same identical form as the shims 16, with the continuous type of joint bar, whereas the base shims 20a and 21a each comprise only two legs, a vertical leg 22a bearing against the rail web 3 and a leg 23a bearing against the top slope of the flanged bases 55 4 of the rails 1 at the bar ends. It will be seen that this construction also provides in effect an arched bar which when assembled will truss up the rail ends at the center of the joint.

60 The provision of shims as described permits the use of a joint bar of uniform section throughout, and with inner surfaces parallel to corresponding surfaces of the adjacent rails and thus obviates the necessity of making any change 65 in the standard forms of joint bars. All wear takes place upon the shims rather than the bars of a joint, so that by replacing the shims from time to time, the efficiency of the rail joint may be maintained over a long period of years without 70 the necessity of replacing the joint bars.

It will be noted that the shims 16, 20 and 21 may be applied to an ordinary joint bar without changing the configuration of the bar at the fishing angles. For example, the bars used may 75 be reformed to a less dimension between the fish-

ing surfaces or longer bolts may be used with a bar of standard dimensions set away somewhat from the longitudinal axis of the rail.

Where, due to wear at the ends of rails or due to batter at a joint, the top surface of a rail head 80 has become depressed, and it is desired to truss the rail head up into line, this may be accomplished by the introduction of shims according to the practice of this invention. By tightening the bolts at the joint, the rail ends may be bent upward in such manner as to align the top surface of a rail head with the level of the rest of the rail, or the rail ends may be trussed up even higher to postpone the time when they will be again battered down in service.

90 The shims or wearing pieces are preferably made of softer material than that used for the joint bars and rails; and as the shims take all the batter or wear and relieve the joint bars, which are of harder material, from wear, the periodic substitution of new shims which are comparatively inexpensive obviates the necessity of reforming the joint bars or cutting off the rails to re-establish proper dimensions at battered rail ends or at the centers of joint bars.

95 While I have described my invention in some detail with reference to one example or embodiment and a modification thereof, it will be apparent that various changes may be made as to the form of shims and bars which may be used 100 without departing from the spirit of my invention as defined in the annexed claims. For example, it will be apparent that in place of three separate shims spaced in the manner described, a single shim might be employed involving three 105 elements similar to the head and base shims which have been described. Furthermore, those skilled in the art will recognize that the invention is obviously applicable to many forms of joint bars other than that here selected for purposes of 110 illustration.

Having thus described my invention, I claim:

1. In combination a rail joint bar having a uniform cross section throughout its length, and shims disposed between the bar and a pair of 120 adjoining rails to provide a three-point contact therebetween, one point of contact being between the heads of adjoining rail ends and the middle of the bar, and the other points of contact being between the bar ends and the rail bases and the 125 bar being otherwise free of engagement with the rails.

2. In combination, a rail joint bar of uniform cross section throughout its length having a head portion conforming to the underside of the rail 130 heads and a base portion conforming to the tops of the flanges of adjoining rails, a shim disposed between the bar and rails to provide head contact at the rail ends but not elsewhere, and additional shims disposed between the bar and rails 135 to provide base contact at the bar ends but not elsewhere.

3. In combination a rail joint bar of uniform cross section throughout its length having a head portion conforming to the underside of the rail 140 heads and a base portion conforming to the tops of the flanges of adjoining rails, a shim disposed between the bar and rails to provide head contact at the rail ends but not elsewhere, and additional shims disposed between the bar and rails 145 to provide base contact at the bar ends but not elsewhere, the inner ends of said base shims being in vertical line with the ends of said head shim.

4. In a rail joint, the rails, a joint bar of uniform cross section throughout its length and of 150

- less fishing height than the fishing height of the rails, shims interposed between the ends of the joint bar and the base flanges of the rails, and a shim of less length than the joint bar interposed between the medial portion of the head of the bar and the undersides of the rail heads at the ends thereof, the bar being otherwise free of engagement with the rails.
5. In a rail joint, the rails, a joint bar of uniform cross section throughout its length having head clearance at its ends from the undersides of the rail heads and being in load supporting relation medially with the ends of the rail heads and otherwise free of engagement with the rail
- heads, and shims interposed between the ends of the joint bar and the rail flanges, the bar being otherwise free of engagement with the rail flanges.
6. In a rail joint, the rails, a joint bar of uniform cross section throughout its length supported outwardly of its medial portion upon the rail flanges and having clearance medially from the rail flanges, said bar having head clearance at its ends from the rail heads, and a shim interposed between the medial portion of said bar and the rail heads.
